UNITED STATES PATENT OFFICE.

WILLIAM L. WEBER, OF BOSTON, MASSACHUSETTS.

VEGETABLE-PEELING APPARATUS.

No. 854,258.

Specification of Letters Patent.

Patented May 21, 1907.

Application filed August 17, 1906. Serial No. 330,941.

To all whom it may concern:

Be it known that I, WILLIAM L. WEBER, of Boston, in the county of Suffolk and State of Massachusetts, have invented certain new and useful Improvements in Vegetable-Peeling Apparatus, of which the following is a specification.

This invention relates to vegetable peeling apparatus.

10 In particular, it relates to apparatus for decorticating and at the same time cleaning in quantity potatoes or other vegetables.

15 It is the object of the invention to provide improvements in such mechanism, particularly with reference to obtaining a more rapid and at the same time gentle action upon the surface of the vegetables to remove the skin, and also to increase the capacity and improve the operation of machines of any given 20 size, and in general to provide apparatus having the other peculiar advantages of the invention hereinafter described.

25 In the accompanying drawings,—Figure 1 shows one form of the apparatus in perspective; Fig. 2 shows the same in longitudinal sectional elevation; Fig. 3 shows one form of roughened surface for the interior of the cylinder wall; and Fig. 4 shows a section through the cylinder wall displayed in Fig. 3.

30 Referring to the drawings: 1 is a tank or trough suitable for holding water, which may enter through the supply pipe 2, and which when ordinarily in operation will maintain the level indicated at 3 in Fig. 2, flowing off through pipe 4. The tank may be drained through pipe 5 at will. The ends 6 of the tank contain journals 7, 7 for axles 8, on which the rotating receptacle 9 is mounted. The latter may conveniently be made fast by

40 keys 10, and may be turned by a crank 11 or such other device as desired. Each axle 8 also carries an eccentric framework or spider 12, 13, the spider 12 being set in a position 180 degrees distant from the position of the spider

45 13 with respect to the axis of rotation. The two are connected by metal sheeting 14 arranged in cylindrical form, as clearly shown in Figs. 1 and 2, the axis of the cylinder being oblique to the axis of rotation. The result is 50 that when the crank is rotated the cylindrical receptacle rotates and alternately assumes the position inclined downward to the left, as shown, and a symmetrical position inclined downward to the right, passing through all

55 intermediate positions during its revolution of 180 degrees from one to the other position.

Two doors 15, 16 are provided in the end wall at one end of the tank, by which vegetables may be inserted and removed. By turning the receptacle to a position with its end 13 60 upward, a position 180 degrees removed from that illustrated in the drawing, and by sliding door 15 upward, the receptacle may be readily filled with vegetables with the aid of the hopper 17. By stopping the rotation at 65 the position shown in Fig. 2, and draining the water to a proper level, door 16 may be opened, swinging outward about hinge 18, whereupon the entire contents of the receptacle will easily roll out and be discharged by 70 the spout 19. When closed, the door 16 is locked by a bolt 20, having an oblique or cam shaped surface 21, by which the door may be closed as tightly as desired to prevent escape of water. 75

Water is introduced through supply pipe 2, which may be arranged at any place desired. It is one advantage of the invention, however, that this water can be introduced in the form of an axial jet, and it is preferred 80 to so arrange the apparatus, the jet then having free and unobstructed play with any force desired upon the surface of the mass. When thus constructed one of the axles 8 is hollow and a nozzle 24 is fixed within the 85 axle, taking water from the supply pipe and discharging it within the cylinder, as shown. The water may be maintained at any desired level, but it is found best to have the same some distance above the lowest level attained 90 by the receptacle, so that each end shall alternately be in the water and out of it, and the water will give some buoyancy to the mass of potatoes.

The cylindrical walls of the receptacle may 95 have such surface as is suitable for decorticating or removing the skin from the potatoes or other vegetables. A quick acting surface is illustrated in Figs. 3 and 4 and is formed by punching holes 22 through a sheet metal plate with a dull instrument, leaving rough edges 23 projecting inward. This makes a grating surface. In cases where the skin is loosely attached, or the vegetables are in suitable condition their abrasive action 105 upon one another may be sufficient to remove the skin, and in such cases the receptacle walls may be smooth. The stationary end walls of the tank may also be roughened if desired. 110

The omission of end walls continuous with the body of the rotating receptacle both re-

duces the cost, simplifies the process of manufacture, and increases the decorticating action.

In operation, when the receptacle is rotated, the mass of potatoes shown in Fig. 2 will gradually roll by force of gravity in a helical path toward the corner which is now upmost opposite the present position of the mass, and will then return by another helical path to their present position. A single rotation of the drum causes them to traverse a long path with a gentle slope, the apparatus being in this respect an improvement over those in which vegetables are rotated in a cylinder set directly on its own axis. The vegetables turn over and over while traveling this path, rubbing against each other and against the roughened walls of the receptacle. The water assists in stopping the impact of the potatoes at the end, by its buoyant effect adds to the agitation, and facilitates the turning and at the same time washes away the loosened bits of skin, and cleans the vegetables. An interaction also takes place between the vegetables and the stationary end walls of the trough. When the upper units in the mass illustrated in Fig. 2 begin to roll away, as the receptacle rises in its path from the low position there pictured, the under units near the stationary end wall are at the same time subjected to friction against that wall primarily, and sec-

ondarily against each other. Consequently, substantially all parts of the mass are subject to decorticating at the same time; and this is great in amount per revolution, owing to the long helical path of each unit.

I claim:

1. A cylindrical receptacle having decorticating surfaced walls and means to rotate it about an axis oblique to the axis of the cylinder.

2. A cylindrical receptacle having decorticating surfaced walls, and means to rotate the receptacle about an axis oblique to the axis of the cylinder, the cylinder being closed at its ends by walls perpendicular to the axis of rotation.

3. In apparatus of the class described, a cylindrical receptacle having open ends and a free space for contents, and having decorticating surfaced walls, and means to rotate the receptacle about an axis oblique to its own axis, in combination with stationary walls set perpendicular to the axis of rotation, closing said open ends and exposed to abrasive contact with the contents of the receptacle.

In testimony whereof I have affixed my signature, in presence of two witnesses.

WILLIAM L. WEBER.
